COMBINATION TYPE ELECTRICAL SWITCH

Jack A. Lawler, Montoursville, Pa., and Frank C. Best, Detroit, Mich.

Application March 18, 1939, Serial No. 262,626

9 Claims. (Cl. 200—43)

The present invention relates to a new and useful combination type electrical switch particularly intended for use in operating doorbells, but with many other useful adaptations.

Heretofore, householders have been annoyed by itinerant agents, peddlers, salesmen, etc., ringing the doorbell and intruding upon the privacy of the home.

An object of the present invention is to prevent undesirable callers from ringing the doorbell without inconveniencing legitimate callers. This is effected by requiring the caller to press certain combinations of buttons, preferably designated with letters, to operate the doorbell.

A further object of this invention is to prevent callers who do not know the tenant's name from operating the doorbell. This is effected by adjusting the switch so that it will operate the doorbell only when buttons, preferably those corresponding to the first two letters of the tenant's last name are depressed.

A further object of this invention comprehends the provision of a simple circuit breaking arrangement so that if more than the proper buttons are depressed the circuit is opened and the bell will not operate. This arrangement includes connecting all contacts, for all of the buttons, in series.

Another object of this invention is to provide a method for preventing detection of the proper buttons (either by sight or feel) by maintaining all the buttons at the same height (when the switch is not being operated) and by maintaining substantially uniform spring pressure and travel on the "live" and "dead" buttons.

Another object of the invention is to provide an external adjustment, so that the switch can be set for various button combinations without disassembling the unit or changing the wiring.

Another object of the invention is to provide an adjustment for setting the button combination which automatically controls the circuit breaking system.

Another object of the invention is to provide an adjustment which can be set from the back of the switch so that proper spacing of the contacts can be accurately determined by the number of turns of the adjusting screw, without using gages.

Another object of the invention is to provide night illumination of the instruction plate and buttons by a small hooded bulb, controlled by a spring returned switch, constructed and so located that it will not be confused with the bell operating means, and the circuit for the switch

and light operating over the conventional wiring system, with no changes in the latter.

A further object of the invention includes parts arrangement which makes possible slim, modernistic styling of the entire switch, and also contributes to ease of manufacture with a minimum of intricate parts.

The above and other objects of the invention will appear from the following description and appended claims when considered in connection with the accompanying drawings forming a part of this specification in which like reference characters designate corresponding parts in the several views.

15 In said drawings:

Figure 1 is a front view of the device showing the light control, instruction plate, and button arrangement.

Figure 2 is a vertical staggered section taken on line 2—2 of Fig. 3 showing the light and the mechanism of the control switches.

20 Figure 3 is a vertical section taken on line 3—3 of Fig. 2 showing the light and the mechanism of the control switches.

Figure 4 is a rear view showing the electrical connections and adjusting mechanism.

Figure 5 is a horizontal section on line 5—5 of Fig. 2, illustrating the adjustment before setting for the desired letter combination.

30 Figure 6 is a typical horizontal section illustrating how the circuit is broken if a "dead" button is depressed.

Figure 7 is a typical horizontal section illustrating the adjustment of a "live" button.

35 Figure 8 is a typical horizontal section illustrating how the circuit is closed when a "live" button is pushed.

Figure 9 is a wiring diagram illustrating a typical setting of the combination.

40 Before explaining in detail the present invention it is to be understood that the invention is not limited in its application to the details of construction and arrangement of parts illustrated in the accompanying drawings, since the invention is capable of other embodiments and of being practiced or carried out in various ways.

Also it is to be understood that the phraseology or terminology employed herein is for the purpose of description and not of limitation, and it 45 is not intended to limit the invention claimed herein beyond the requirements of the prior art.

As seen in the drawings, construction and operation of the preferred embodiment is as follows:

50 A molded plastic housing 1 retains all of the

mechanism of the device as a unit and is mounted in place by screws 2 and 3. Screw 2 is driven into the mounting surface 4 until a predetermined space exists between the rear side of the screw flange 5 and the mounting surface 4. A flange 6 on the upper rear portion of the housing is designed to be interposed between the screw flange 5 and the mounting surface 4 by a hooking action after screw 2 is in position. By this method of attachment the exterior of the upper end of the housing 1 is free from the presence of unsightly mounting screws and the styling is clean and unbroken. At its lower end, the housing 1 is provided with a screw boss 7 for the lower attaching screw 3 which has a hollow hexagon head 8 for driving purposes, requiring a special wrench for installation and removal, thus minimizing the possibility of theft or tampering.

In the rear interior of the housing 1 and secured by screws 9 is a fiber plate 10 on the rear surface of which are mounted brass electrical connector bars 11 secured in place by rivets 12 and having at their ends tapped holes 13 provided with splits 14, the spring action of which insures a tight grip on the contact screws 15, thus preventing lost motion and rotation of the latter after adjustment. In manufacturing assembly, these contact screws 15 are adjusted by a screwdriver at the slotted ends 16 until a predetermined clearance exists between the rear sides of the contact screw heads 18 and the front face of the fiber plate 10. Across each pair of oppositely disposed contact screws 15 is installed a contact bridge 19 positioned in vertical and lateral alignment by openings 25 in housing 1, the ends of which bridge are of hooked form, and the termination of each end 20 being disposed between the rear side 17 of the contact screw head 18 and front surface of the fiber plate 10. Pins 21 pressed into the fiber plate 10 locate coil springs 22 which exert pressure between the front face of the fiber plate 10 and the rear surfaces 23 of the contact bridges 19 thus normally maintaining the front surfaces 24 of the terminations 20 of the contact bridges 19 in positive contact with the rear sides 17 of the contact screw heads 18. It will be observed that the oppositely disposed rows of connector bars 11 on the rear surface of the fiber plate 10 are arranged in staggered formation in order that the connectors 11, the contact screws 15 and the contact bridges 19 will cooperatively form series arranged components of an electrical circuit when desired, as shown in Figure 9.

In the front face of housing 1 are rectangular openings 26 through which project push buttons 27, the latter being provided with holes 29 to receive very light coil springs 30, the ends of the latter resting on the front surfaces 31 of the contact bridges 19 and the springs 30 acting to force the push buttons 27 outward, this movement being limited by the flanges 28 of the former when coming to rest on the inside surface 32 of the front of the housing 1. By the use of the springs 30 the buttons 27 are all maintained level and this feature combined with the spring pressure reaction when the buttons are pushed serves to maintain uniform appearance and feel of "live" and "dead" buttons, thus minimizing the risk of an unauthorized person's succeeding in detecting the pre-selected buttons utilized for operation of the door-bell.

Due to the manufacturing assembly adjustment of the contact screws 15, a predetermined space

will exist between the rear surfaces 33 of the buttons 27 and the front surfaces 31 of the contact bridges 19. This space is for clearance purposes in order to insure positive contact between the contact bridge 19 and the contact screws 15, when the former is pushed forwards by springs 22. Figure 5 illustrates the positions of the various parts related to each pair of oppositely disposed contact screws 15 after final assembly. It will be noted that electrical contact has been made between contact bridge 19 and both contact screws 15.

Figure 7 illustrates the positions of the various parts related to a pair of oppositely disposed contact screws 15 after one of these screws has been adjusted in order to permit the control button 27 in front of it to be active in closing an electrical circuit when pushed. It will be observed that the rear face 17 of the contact screw head 18 has been moved outward sufficiently from the front surface 24 of the contact bridge termination 20 to break electrical contact at this point. The force of spring 22 has overcome that of the very light spring 30 and has forced one end of the contact bridge forward to where its outside surface 31 contacts the inside ledge 34 of the case 1. This abutment assures a positive relation between the rear surface 23 of the contact bridge 19 and the front surface 35 of the contact screw 15 in order that travel and clearance at this point may be held to constant dimensions. Figure 8 illustrates how contact is made in an electrical circuit when a preselected button utilized for the operation of the device is pushed. Pressure on button 27 pushes one end of the contact bridge rearwardly where its rear surface 23 contacts the front surface of the adjusting screw head 18.

Figure 6 illustrates the result of pushing a button not preselected for the operation of the device. It will be noted that pressure on the button 27 pushes one end of the contact bridge 19 rearwardly thus breaking the contact between the front face 24 of the contact bridge termination 20 and the rear face 17 of the contact screw head 18. This prevents the possibility of an unauthorized person pressing all of the buttons at the same time in order to defeat the purpose of the device. Figure 9 illustrates a wiring diagram wherein the connector bars 11, the adjusting screws 15 and the contact bridges 19 all co-operatively form series arranged components of an electrical circuit including a source of electrical energy, in this case a transformer 36 and an electrically operated device, in this case a door bell 37, when the proper buttons are pushed simultaneously. In the illustration, contact screws 15, shown lightly shaded, are non-effective in the operation of the device and are in contact, while those shown in black are pre-selected and are normally out of contact. Pressing the buttons associated with the latter contact screws simultaneously, closes the circuit and the device is then in operation. It might be noted that oppositely disposed buttons associated with the same contact bridge may be pre-selected as also may any number of buttons if so desired for specific applications. For the purpose of night illumination of the buttons and the direction plate 38, a low candlepower, high resistance bulb 39 is located in a hooded projection 40 at the top of the housing 1. This bulb is mounted as a unit with a spring return switch 41 on a mounting plate 42 secured by screws 43 to the rear of the housing 1. The switch 41 is operated by a lever

44 and pull chain 45 and remains in contact only when the chain 45 is held down. As access to the bulb and switch unit is only from the rear of the housing 1, theft of the bulb is prevented. The bulb 39 and switch 41 are shown in Figure 9 in series and are in parallel with the terminals 9 of the combination control unit. When the switch 41 is closed, the bulb 39 is then in series with the transformer 36 and the bell 37. The combined high electrical resistance of the bulb 39 and the magnet coil of the bell 37 will allow a small amount of current to flow through the bulb filament for illumination, but the current flow will be insufficient to operate the bell. By this method, additional wiring is not required when replacing the conventional door bell switch with this device.

From the drawings and the foregoing description it will be readily apparent that when this device is utilized in connection with a doorbell that the buttons will be designated with letters of the alphabet and that a person desiring to ring said bell must push buttons preferably corresponding to the first two letters of the tenant's last name simultaneously in order to obtain results. Thus much annoyance and inconvenience is spared the tenant, while at the same time legitimate callers are not put to any inconvenience. It will also be observed that if a person tries to push the right buttons by pushing a group of or all of the buttons the circuit is automatically broken and his attempts to ring the bell are frustrated. Because of the mechanism employed, it will be observed that detection of the proper buttons by sight or feel will be improbable. It will also be seen that the device can be set for any name without dismantling the unit or changing the wiring and that the circuit breaking contacts are automatically controlled by the position of the adjusting screws.

It will also be readily apparent to one experienced in the art that the use of this device need not be restricted to doorbell control alone, and that there are numerous applications of the device to meet conditions where combination control is desirable. It is also possible to use the contact mechanism in other forms of electrical switch and control mechanisms where combination control is not necessary.

We claim:

1. In an electrical switch, a movable contact with spaced surfaces, a normally stationary contact with a portion extending between the surfaces of the movable contact, a spring forcing the movable contact in one direction to establish electrical contact between one surface of the movable contact and the said portion of the stationary contact, means limiting the travel of the movable contact when moved by the spring, and means to adjust the stationary adjustable contact to a position out of normal electrical contact with the movable contact.

2. In an electrical switch, the combination of a pair of electrical conductors, spaced adjustable contact screws associated with each conductor, flanged heads on said contact screws, a movable electrical conductor with opposed hook shaped ends, said hooks partially enclosing the flanges of the adjustable contact screws, spring means for maintaining contact between the movable electrical conductor and the flanged heads of the contact screws, and push button means for breaking said contact.

3. In an electrical switch, a housing having a wall, a pair of electrical conductors secured to

said wall and securing adjustable contact screws having flanged heads spaced from said wall, a movable contact with opposed hooked ends, said hooked ends enclosing the flanges of the contact screws, spring means biasing said movable contact in one direction, push buttons at each end of the movable contact to move it against said spring means, and a spring between each end of the movable contact and its button.

4. In an electrical combination type switch, a plurality of switches connected in series, each including a movable contact, a normally fixed contact and adjusting means to position said normally fixed contact so that its switch is normally open or normally closed, a mounting for said adjusting means, push buttons mounted upon and restrained for limited movement by said mounting, and spring means between said push buttons and said movable contacts to force said push buttons out to the full extent of their limited movement.

5. In an electrical combination type switch, a housing, an electrically insulating structure associated with said housing, spaced electrical conductors arranged in oppositely disposed staggered rows on said structure and secured thereto, normally stationary contacts in said housing and associated with the ends of said electrical conductors, said contacts being adjustable for a normally open or closed circuit position, cooperating movable contacts in said housing and selectively engaging oppositely disposed adjustable contacts to connect them in series, push buttons on said housing each designated by identification means and substantially in line with each movable contact to actuate it.

6. In an electric switch, a first switch element having two spaced contact surfaces, a second and cooperating switch element having a contact portion between said two surfaces, one of said elements being movable in a direction transverse to said surfaces, stop means to limit the movement of said movable element in either direction, and the other element being adjustable to either of two normally fixed positions, one in which the normally engaged elements are separated to open the switch upon movement of said movable element and the other in which the normally disengaged elements are engaged to close the switch upon the same movement of the said movable element.

7. An electric switch unit comprising a closed casing, means to open or close an electric circuit therein, means projecting into said casing manually movable in one direction to actuate said first means, and means including an adjustably movable member projecting into said casing to adjust said first means so that the circuit will be either opened or closed upon the one direction of manual movement of said second means.

8. A readily installable combination type switch unit comprising a closed casing having a back and a front and adapted to be fixedly secured with its back against a wall or the like so that its back is inaccessible after installation, electric terminals on its back, a plurality of adjustable switches in said casing connected in series between said terminals, certain preselected normally open switches being closed on actuation and the remaining normally closed switches being opened upon actuation, manually operable means with suitable indicia on the front of said casing and extending therein to selectively actuate each of said switches, and means including a plurality of adjustably movable members on

the back of said casing and projecting therein to selectively adjust said switches to set up any desired combination without any rewiring or opening of the casing.

9. A combination type electric doorbell switch unit comprising an upright elongated slim casing having a front, two upright rows of indicia carrying push buttons on its front in side by side pairs and projecting therein, a plurality of switches connected in series in said casing, certain switches being normally open and the remainder being normally closed, said switches consisting of

a single upright row of movable contact members, each contact member having two laterally extending ends positioned behind the two buttons of a pair of buttons and being movably mounted so that the two ends thereof may be actuated independently by the two buttons of the corresponding pair, and a plurality of normally fixed contact members positioned with one to cooperate with each end of each movable contact member.
